(57) **CLAIM**

The ornamental design for a shoe cover, as shown and described.

DESCRIPTION

FIG. 1 is a left side elevational view of a shoe cover;

FIG. 2 is a rear elevational view thereof;

FIG. 3 is a right side elevational view thereof;

FIG. 4 is a front elevational view thereof;

FIG. 5 is a bottom plan view thereof;

FIG. 6 is a top plan view thereof;

FIG. 7 is a top perspective view thereof;

FIG. 8 is a bottom perspective view thereof;

FIG. 9 is a rear left perspective view thereof; and,

FIG. 10 is a closeup view of 10-10 in FIG. 9 showing the strap and clip.
The broken line showing person is included for the purpose of illustrating environmental structure and forms no part of the claimed design.
